CLAIM

The ornamental design for a display screen with graphical user interface, as shown and described.

DESCRIPTION

FIG. 1 is a first view of a display screen with graphical user interface showing our new design;

FIG. 2 is a second embodiment thereof;

FIG. 3 is a third embodiment thereof; and,

FIG. 4 is a fourth embodiment thereof.

The short, intermediate and dashed broken lines in the drawings illustrate portions of the display screen with graphical user interface that forms no part of the claimed design.

1 Claim, 4 Drawing Sheets
